UNITED STATES PATENT OFFICE.

JAMES MANN, OF DOWAGIAC, MICHIGAN.

GARBAGE-BURNER AND WATER-HEATER.

SPECIFICATION forming part of Letters Patent No. 718,490, dated January 13, 1903.

Application filed March 25, 1902. Serial No. 99,887. (No model.)

To all whom it may concern:

Be it known that I, JAMES MANN, a citizen of the United States, residing at Dowagiac, in the county of Cass and State of Michigan, have 5 invented certain new and useful Improvements in Garbage-Burners and Water-Heaters, of which the following is a specification.

My invention relates to a garbage-burner, in its preferred form to a combined garbage- 10 burner and water-heater, the object of which invention is to provide a simple and efficient device of this character and one capable of utilizing the heat for the purpose of heating water.

15 The points of advantage and utility in the construction and arrangement of my garbage-burner will be apparent from the description hereinafter given.

In the drawings, Figure 1 is a plan view of 20 my garbage-burner; Fig. 2, a side elevation thereof; Fig. 3, a sectional plan on the line A B of Fig. 4; Fig. 4, a sectional elevation on the line C D of Fig. 3, and Figs. 5 and 6 modifications of the garbage-grate and associated 25 parts.

As wood, hard coal, soft coal, or gas may be the fuel employed for the drying and initial burning of the garbage, provision is made in my burner, about to be described, for the use 30 of either one of these kinds of fuel, comparatively slight changes being made to adapt the burner to the particular fuel employed, such changes not necessitating a departure from the general principle of my invention.

35 Referring first to the hard-coal-burning apparatus, my burner, which is preferably a cylindrical shell, comprises the lower section or shell 1 and the upper section or casing 2, the former containing a fire-grate 3, forming 40 below an ash-pit 4. This lower section supports in a suitable manner the upper section 2, which has double walls 5 and 6, forming between them a water space or jacket 7. In order to prevent clogging or packing of the 45 garbage in a solid mass, which would choke or stop the draft, and also to increase the heating-surface of the water-jacket, the inner wall 6 is made corrugated or fluted, as seen in Fig. 3. The upper section or shell 2 is 50 closed at its top by a plate or cover 8, supported thereon and provided with a depending magazine 9, adapted to feed coal—hard

coal in the present instance—to the fire-chamber 10. By preference this magazine is cylindrical at its lower end, but elliptical at its 55 upper end, Fig. 1. This top plate or cover is provided with a plurality of doors 11, whereby the garbage may be supplied to the garbage-burning space or chamber 12. Surrounding each door-opening on three sides is a hopper 13, which has an inner portion or wall 14 extending to the edge of the door-opening, such arrangement facilitating and making more convenient the feeding of the garbage 60 to the burner.

Within the upper section or shell 2 at the lower end of the garbage-chamber and above the fire-chamber is arranged a garbage-support 15, which may be said to separate the fire-chamber from the garbage-chamber and 7c which has a central opening to receive the magazine, projecting a slight distance through it and into the fire-chamber, as seen in Fig. 4. The garbage-support is inclined and is slightly less in diameter than the inside measurement 75 of the shell 6, whereby an annular space is left for a purpose hereinafter explained.

The garbage-support, which in the present instance is shown as substantially truncated conical, is cast hollow to form the water-space 80 16, through which water way circulate, and is provided with a plurality of transverse fire-openings 17. The garbage-support may be supported in suitable manner within the shell or casing 2 and may also be suitably connected as to its water-space with the water space or jacket 7, and in the present instance I have utilized such water connection as such support, whereby such water connection or pipe has a twofold function, as shown. Short 85 pipes 18 screw through the inner walls 6 of the shell or section 2 and enter screw-threaded holes, which communicate with the water-space of the garbage-support. As illustrated in Fig. 3, a hot-water pipe 19 leads from substantially the highest and hottest point of the garbage-support above the plane of the pipes 18 up through the garbage-chamber, and, as illustrated in Fig. 4, the water space or jacket 7 is provided with a supply or intake pipe 20. 90 The direction of circulation of the water is downwardly through the water-jacket at the coolest point through the short pipes 18 and 95 through the garbage-support, and finally up- 100

wardly through the hot-water pipe 19, leading from the hottest point to a suitable reservoir or place of use.

As herein shown, the garbage-support is substantially cylindrical at its lower portion, while its upper portion slopes gradually inwardly and upwardly from the upper corner or margin of such cylindrical portion. This support, which is an integral structure or casting, as illustrated, with an interior water-space and transverse fire-openings, is of slightly less diameter than the inner shell or casing, whereby an annular space is left or formed between such casing and such cylindrical portion of the garbage-support. The short transversely-arranged pipes, as hereinbefore described, pass through such inner casing, across the annular space, and into the sides or cylindrical portion of the garbage-support, thereby accomplishing the twofold function hereinbefore mentioned.

From the foregoing explanation the operation of my burner is obvious. The heat of the coal supplied from the magazine will keep drying and burning the garbage coming in contact with the garbage-support and the products of combustion passing from the garbage-chamber through the flue 21 at the top. Thus the garbage will be dried and will slide down the inclined support and, falling through the annular opening at the edge of the support, will be effectually consumed and disposed of in the fire-chamber below, and at the same time the heat of combustion will be utilized in heating the water in the garbage-support and in the water-jacket. Of course the top of the magazine may be provided with any suitable lid, such as the lid 22.

The corrugating of the inner wall of the upper shell serves the twofold function of increasing the heating-surface and of preventing the packing of the garbage in a solid impenetrable mass at the sides, so that the draft through the garbage-chamber will never be fully obstructed.

As hereinbefore suggested, my garbage-burner may be adapted for the burning of soft coal, as well as of gas, such adaptation being possible by the making of very simple changes in the construction already described.

Referring to Fig. 5, the garbage-support here shown is adapted for soft coal. Consequently the coal-magazine useful for hard coal is dispensed with and the coal is introduced through the fire-door 2^b. In order to supply the proper amount of air in addition to that supplied through the ordinary damper 2^a in the fire-door, I provide a down draft or current of air, whereby complete combustion of the coal is possible. To this end an air-pipe 23 is screwed into the garbage-support, which has a smaller central opening than that illustrated in Fig. 4. This pipe is secured to a disk or plate 24 at its upper end, which plate takes the place of the lid 22. Under this arrangement air is drawn downwardly through the air-pipe and supplied to the fire-chamber.

If desired, the upper end of the air-pipe 23 may be provided with any form of damper or regulator 25, which may be suitably pivoted and permit a greater or less opening at the upper end of such pipe. 70

Referring to Fig. 6, the garbage-support here shown is adapted for the burning of gas as the fuel, and in this instance a pipe 26, which is a water-pipe, screws into the garbage-support in such manner as to communicate with its water-space, such pipe corresponding to and taking the place of the hot-water pipe 19. (Illustrated in Fig. 3.) This hot-water pipe may be suitably supported at its upper end in a manner similar to pipe 23 by means of a disk 27. 80

If desired, several lugs 28 may be provided on the inner wall 6 to steady the garbage-support, especially in shipping from the shop or factory, when wooden blocks would be driven down between such support and the wall 6. 85

I claim—

1. In a garbage-burner, the combination of a shell or casing having a fire-chamber and a garbage-chamber, and a garbage-support arranged in said casing to separate said chambers and of slightly less diameter than such casing, said support being outwardly and downwardly inclined and consisting of a hollow water-containing casting having fire-openings. 90

2. In a garbage-burner, the combination of a shell or casing having a fire-chamber and a garbage-chamber, and an inclined garbage-support arranged in said casing to separate said chambers and of less diameter than such casing so as to have an opening for the downward passage of burned garbage or ashes, 100 said garbage-support being inclined outwardly and downwardly. 105

3. In a garbage-burner, the combination of a shell or casing having a fire-chamber and a garbage-chamber, a garbage-support arranged in said casing to separate the chambers and of slightly less diameter than such casing, said support being a hollow water-containing casting having fire-openings, and water-supply connections entering through 115 the casing and communicating with the hollow support. 110

4. In a garbage-burner, the combination of a shell or casing having a fire-chamber and a garbage-chamber, a garbage-support arranged in said casing to separate the chambers and of slightly less diameter than such casing, said support consisting of a hollow water-containing casting outwardly and downwardly inclined and having fire-openings, and short water-supply pipes passing through said casing and into said casting, thereby forming a combined water-supply connection and a support for the casting. 120

5. In a garbage-burner and water-heater, 130 the combination of a shell or casing having a fire-chamber and a garbage-chamber, a garbage-support arranged in such casing to separate said chambers and of slightly less di-

ameter than such casing, thereby leaving a space between such casing and support, said support being an integral structure which has an interior water-space and transverse fire-openings, and transversely-arranged water-pipes passing through said casing, across said space and into the sides of the said support.

6. In a garbage-burner, the combination of a shell or casing having a fire-chamber and a garbage-chamber, a garbage-support forming such chambers and provided with a substantially central opening, and a pipe depending through the garbage-chamber and through the support into the fire-chamber for the supply of fuel or air thereto.

7. In a garbage-burner and water-heater, the combination of a shell or casing having a fire-chamber and a garbage-chamber, a garbage-support arranged in such casing to separate said chambers and of slightly less diameter than such casing, thereby leaving an annular space between such casing and support, said support being an integral structure, circular in outline and having an interior water-space and transverse fire-openings and water-pipes passing through said casing, across said space and into the sides of said support.

8. In a garbage-burner, the combination of a shell or casing having a fire-chamber, and a garbage-chamber, a garbage-support forming such chambers, and a magazine depending through the garbage-chamber and through the support into the fire-chamber.

9. In a garbage-burner and hot-water heater, the combination of a shell or casing, having a fire-chamber, and a garbage-chamber, a water-jacket for such shell, a hollow substantially truncated conical garbage-support forming said chambers and having a water-space communicating with said water-jacket and a magazine depending through the garbage-chamber and centrally through the support into the fire-chamber.

10. The combination of the shell 2 having the double walls 5 and 6 forming the water-jacket 7, a hollow garbage-support 15 having a water-space 16 and transverse fire-holes 17, pipes 18 extending through wall 6 and into the grate to communicate with its water-space, an outlet-pipe 19 from the support, an inlet-pipe 20 to the water-jacket and a depending magazine 9 passing through said garbage-support.

11. The combination of the shell 2 having the double walls 5 and 6 forming the water-jacket 7, a hollow garbage-support 15 having a water-space 16 and transverse fire-holes 17, pipes 18 extending through wall 6 and into the

support to communicate with its water-space, a depending magazine 9 passing through the grate, an outlet-pipe 19 leading upwardly from substantially the highest point of the support and an inlet-pipe 20 entering the jacket near 65 its top.

12. In a garbage-burner and water-heater, the combination of an inner shell or casing having a fire-chamber and a garbage-chamber, an outer shell or casing forming a water-jacket in connection with the inner shell, a garbage-support arranged in the inner casing to separate the said chambers thereof and of slightly less diameter than the inner casing to thereby leave a space between such latter 70 casing and the support, said support being an integral structure, having an interior water-space and transverse fire-openings, and water-pipes passing through such inner casing, across said space and into the sides of said 80 support.

13. In a garbage-burner, the combination of a shell or casing having a fire-chamber and a garbage-chamber, a garbage-support arranged in said casing to separate the chambers and comprising an integral structure substantially cylindrical at its lower end and sloping gradually upward and inward from the top edge of the cylindrical portion, which portion is of slightly less diameter than such 90 casing to leave an annular space between said casing and such cylindrical portion of the support, and supports passing through said casing, across said annular space and into the cylindrical portion of said garbage-support. 95

14. In a garbage-burner, the combination of an inner cylindrical shell or casing having a fire-chamber and a garbage-chamber, an outer cylindrical shell or casing forming a water-jacket in connection with the inner shell, 100 a garbage-support arranged in the inner casing to separate the said chambers thereof and of slightly less diameter than the inner casing to thereby leave a space between such latter casing and the support, said support 105 comprising an integral structure whose lower portion is cylindrical and whose upper portion slopes upwardly and inwardly from the upper edge of such cylindrical portion, said support having an interior water-space and being provided with transverse fire-openings, and short pipes passing through the inner casing and extending into the said support, thereby forming communication between the water-jacket and said water-space in the support. 110
